UNITED STATES PATENT OFFICE.

BERNT JACOBSON, OF MABEL, MINNESOTA.

DESIGN FOR A CALENDAR.

Application filed August 7, 1925. Serial No. 14,336. Term of patent 14 years.

To all whom it may concern:

Be it known that I, BERNT JACOBSON, a citizen of the United States, residing at Mabel, in the county of Fillmore and State of Minnesota, have invented a new, original, and ornamental Design for a Calendar, of which the following is a specification, reference being had to the accompanying drawing, forming part thereof.

The drawing shows a view in front elevation of a calendar showing my new design.

I claim:—

The ornamental design for a calendar, as shown.

BERNT JACOBSON.
